UNITED STATES PATENT OFFICE.

WILLIAM E. CONOVER AND BERT D. BUSH, OF UTICA, NEW YORK, ASSIGNEES TO
UTICA DUXBAK CORPORATION, OF UTICA, NEW YORK, A CORPORATION OF NEW
YORK.

HUNTING COAT.

Application filed April 5, 1928. Serial No. 267,742.

Our invention relates to a hunting coat and we declare the following to be a full, clear, concise and exact description thereof sufficient to enable anyone skilled in the art 5 to which it appertains to make and use the same, reference being had to the accompanying drawings in which like reference characters refer to like parts throughout the specification.

10 The object of the invention is to provide a coat adapted for use more particularly when hunting wild game. To this end the coat is equipped with a large pocket or chamber formed between the two layers of 15 canvas that comprise the outer and inner surface of the coat. Moreover, the lower half of this large pocket is lined with an oil skin or other non-leakable material adapted to prevent blood or other excrecence that 20 drips from the killed game deposited therein from soaking through the material of the pocket and dripping onto the hunter's lower garments with the uncomfortable results arising therefrom. Furthermore, the pocket 25 is arranged whereby it can be turned inside out and the oil skin lining thoroughly washed. This advantage is particularly serviceable inasmuch as it eliminates the unsanitary condition of the lining if left, 30 as heretofore, with the blood stains therein. For it is a well known fact that the decomposing matters will permeate the coat and render an unpleasant odor which is offensive to the sense of smell. This objectionable 35 feature soon compels the owner to discard it for another.

It is for the correction of these and other defects that the coat has been designed. Furthermore, its object will be understood 40 by referring to the drawings in which:

Fig. 1 is a perspective view of the coat showing the inner ply of fabric drawn outward slightly adjacent the arm hole among other features.

45 Fig. 2 is an elevational view of the coat showing the same folded over on itself with the inside outermost.

Fig. 3 is an elevation of the coat folded over on itself with the inside outermost and 50 showing the inner ply of fabric torn open for the purpose of viewing the interior pocket.

Fig. 4 is an elevational view of the coat showing a portion of the inside lining drawn 55 out through one of the apertures, opposite

the arm hole which are made for that purpose.

Fig. 5 is a vertical sectional view taken on the line 5, 5 of Fig. 1.

Referring to the drawings more particularly, the coat 1 is made of canvas sufficiently heavy to be of service in protecting the user in the open against the cold or the inclement and rainy weather. The coat has a corduroy collar 2, sleeves 3, 3 that are left open at the seam adjacent the end, whereby said ends can be turned back and buttoned as shown at 5 in Fig. 1. Corduroy linings 6, 6 are sewed on the inner surfaces of the free ends of sleeves 3, 3 whereby to lay outermost when the end portion is turned back as shown in Fig. 1 to effect a dressy appearance of the sleeve. Moreover, the usual buttons 10 and button holes 11 along the front edges of the garment are employed to button the coat to the wearer. Side pockets 12, 12 are made in the garment. Each of said side pockets, however, is divided by stitches 14. There is also pocket 15 and smaller pocket 16 placed thereover and both disposed on front chest portions of the garment. A tab or loop 17 is sewed at the inside of the garment adjacent the back of the neck portion for use in hanging the coat when not in use.

The coat is made with a double thickness of canvas, except in the arm portions 18, immediately under the pit thereof where there is only one thickness. Holes 19 surrounded with composition eyelets 20 are made 90 through the canvas at these portions in the sleeves for ventilation. The double thickness of canvas forms a large pocket 21 between said layers which is used for carrying the dead game. This pocket can be divided 95 into three compartments, two forward and one in the back of the coat by buttoning the glove fasteners 25. The male part 26, 26 of the fasteners being secured to special strips of fabric 27, 27 which in turn are sewed to the inside fabric of the coat, and the co-operating female parts 28, 28 to the opposite wall of the coat adjacent the vertical pocket openings 30, 30 which give access to the interior of the enlarged pocket formed between 100 the outer and inner plies of fabric 31 and 32. Access to the large pocket may be had also 105 through openings 33, 33 formed in the opposite edges of the coat. An oil skin or other nonleakable lining 34 is sewed to the inside 110

surfaces of the enlarged pocket and covers the entire lower portion thereof, extending from one front edge 35 to the other 36, and across the entire back and half way up between lower edge 37 and arm holes 38, 38, whereby to provide a pocket or bag that will prevent the blood of the wild game carried therein from dripping down therethrough onto the lower garments of the wearer. The upper edge of said oil skin is seamed along three different lines 40, 40, 40 to the respective inner and outer plies of fabric and the lower edge on each surface is turned up and sewed to the turned up edges of the two plies of fabric disposed or sandwiched in between as shown at 45 in Fig. 5.

In order to allow for pulling the inside of this enlarged pocket out, whereby it will be exposed for washing and cleansing purposes, rather large round apertures 46, 46 are made in the inside piece of fabric 31, adjacent or concentric with the arm holes 38, 38, whereby said apertures 46 will serve both as auxiliary arm holes and for the purpose of allowing the inside of the coat to be pulled outermost. Extra bands about an inch wide 50, 50 are sewed to the fabric adjacent the edges of apertures 46, 46 whereby to strengthen said edges.

Having thus described our invention what we claim as new and desire to secure by Letters Patent is as follows:

1. In a hunting coat, a pocket covering the back portion of the coat, armholes formed in said coat and the fabric adjacent the armholes having free edges for permitting the

inside of the pocket to be pulled outermost.

2. In a hunting coat, made of two plies of fabric, a pocket between said plies of fabric, armholes formed in said fabric, the edges of the fabric adjacent certain of said armholes being free, whereby to permit the inside of the pocket to be pulled thereout, to clean said pocket.

3. In a hunting coat, an outer and an inner 45 ply of fabric, a pocket formed between said plies, an oil skin for lining said pocket, and armholes formed in said fabric and the fabric adjacent the armholes having free edges to permit said lining to be drawn there-through, whereby to allow for cleaning said lining.

4. In a hunting coat made of two plies of fabric, armholes formed thereon, a non-leakable lining secured to said plies of fabric, and one of said plies of fabric having apertures formed therein adjacent said armholes, the edges of the fabric adjacent said apertures being free, whereby to allow for drawing said non-leakable lining thereout.

5. In a hunting coat made of two plies of fabric, armholes in one ply of said fabric, a non-leakable lining secured to said plies of fabric and one of said plies of fabric having auxiliary armholes made therein, the edges of the fabric adjacent said auxiliary armholes being free to allow for drawing said non-leakable lining thereout.

In testimony whereof we have affixed our signatures.

WILLIAM E. CONOVER.
BERT D. BUSH.
